UNITED STATES PATENT OFFICE.

SAMUEL K. DENNIS, OF CHICAGO, ILLINOIS, ASSIGNOR TO INTERNATIONAL HARVESTER COMPANY, OF CHICAGO, ILLINOIS, A CORPORATION OF NEW JERSEY.

CULTIVATOR.

Application filed November 12, 1921. Serial No. 514,500.

This invention relates to wheel cultivators of the two-row type. The objects of the invention are to provide a cultivator of that type with guiding means and with beam shifting and adjusting means of simple and economical construction which will enable the driver seated on the machine to quickly and easily change the distances between each pair of beams and also shift them while guiding the cultivator and to provide control mechanisms therefor which permit the beam shifting and the cultivator guiding or steering means to be coupled for joint operation while retaining separate control of the beam adjusting mechanism, and also permit disconnection of the guiding means from the beam shifting means when desired. A further object of the invention is to provide a joint lift for each pair of beams which has means for equalizing the pressure on each beam.

The foregoing objects are accomplished by providing the cultivator with swiveled wheels and mechanism for jointly steering them, and by suspending the beams on laterally swinging members and connecting the beams of each pair by intersecting elements such as crossed arch members, each carrying one beam of each pair and by so connecting beam controlling mechanism to the arches that they may be moved to and from each other to vary the spread of the beams or shifted in unison to follow the rows, the controlling mechanism including a swinging supporting bracket for the beam shifting means, which bracket carries latch mechanism of novel form through which the beam control mechanism can be connected or disconnected from the wheel steering or guiding means.

With these main and other supplemental objects in view, the invention consists of the organization and details of construction set forth in the following description and defined in the claims.

Referring to the drawings—

Fig. 1 is a side elevation of a cultivator embodying my invention.

Fig. 2 is a plan view.

Fig. 3 is a detail view of the crossed arches which carry the beams, taken substantially on line 3—3 of Fig. 2.

Fig. 4 is a detail side view on an enlarged scale of parts of the operating mechanism for the steering and beam shifting means,

Fig. 5 is a sectional view on line 5—5 of Fig. 4.

Fig. 6 is a detail view of the bell crank levers forming part of the beam adjusting means.

Figures 7, 8 and 9 are similar plan views of the sliding latch for connecting and disconnecting the beams and steering means, each figure showing the latch in a different position.

Figures 10 and 11 are plan and side views on an enlarged scale of the sliding latch element and Figures 12 and 13 are similar views of the latch holding element.

My invention is shown as embodied in a two-row cultivator having a main rectangular frame 20, the rear of which is formed by an axle beam 21, on the ends of which are journaled in any suitable manner axles 22 on which are carried the wheels 23. Each axle has a forwardly projecting steering arm 22a and these arms are connected by a radius bar 24 for joint steering movement. The front of the frame has a projecting arch portion 25 secured thereto to the forward end of which is secured a sleeve 26 in which is journaled the upright standard of a front truck 27, supporting the front of the frame. A draft pole or tongue 28 is pivotally connected to the sides of this arch as shown in Fig. 2, and the forward end of the frame is made vertically adjustable by means of a lever 29 pivoted to the sleeve 26 in the manner shown in Fig. 1 and connected by link 30 to a collar 31, which is held between abutments on the standard of the truck. The other end of the lever 29 is connected by a link 32 to a hand lever 33 on the rear of the frame. It will be evident that by reciprocation of link 32 the front of the frame will be raised and lowered on the truck to a sufficient degree to provide depth adjustment for the forward ends of the gangs.

A transverse frame bar 34 to which the arms of the arch 25 are secured is provided intermediate the front and rear frame members and the cultivator beams 35 are suspended from the frame on pendulum rods 36, the two outer rods being hung on the side bars of the cultivator frame and the two inner ones from the transverse bar 34, as best seen in Fig. 3. The beams are also connected to the frame through downwardly and forwardly extending push bars 37, these bars being pivoted on the frame on an

oblique axis at 38. The beams are connected to each other and to the supporting elements 36 and 37 by means of crossed arch members 39 (Fig. 3), these members being 5 formed of single bars or rods with their inner legs projecting inwardly so that they intersect and so that each member 39 will have two horizontal portions 39^a in proper position to have journaled thereon the forward end of one of each pair of beams, as at 40. Each horizontal portion 39^a has secured thereto the spaced arms of a supporting member or bracket 41 which has a forwardly projecting downwardly curved portion 41^a provided with obliquely extending apertures 41^b, 41^c, in which are loosely received the bent ends of the supporting rods 36 and 37 respectively, as best seen in Fig. 1. By the construction above described the 20 crossed arch members 39 are suspended from the main frame in a manner to permit a certain range of lateral swinging movement, either individually or jointly, and the beams of course will follow the movements 25 given the arched members. As controlling mechanism for the arched members, each arch has fixed thereto a rearwardly projecting plate 42, the end of which is provided with a series of openings, one of which receives an inwardly extending rod 43 which rods have their other ends connected to bell 30 crank levers 44 which are mounted between bracket members 45 fixed to a forwardly extending supporting bracket 46 pivotally mounted at 47 on the axle beam 21 of the frame. The bell crank levers 44 are positioned with their inner arms directed toward each other and formed into arcuate racks 44^a with which there meshes a rack 47 on 35 the end of a reciprocating rod 47^a which has its other end connected to an actuating hand lever 47^b mounted on the rear of the frame. It results from this construction that by manipulation of the hand lever 47^b the bell 40 crank levers 44 will be swung and through the links 43 the arch members will be moved to and from each other and the space between the cultivator beams correspondingly 45 adjusted. The transverse frame bar 34 has a bracket 48 centrally secured thereto and beneath this bracket there is pivoted a T-shaped lever 49, the long arm of which is upwardly and backwardly directed and its end slotted at 48^a for engagement with a 50 depending stud 50 on the radius bar 24. The short arms of the T-shaped lever are connected by links 51 to foot levers 52 which are suspended from a bracket 53 secured to frame member 21, the relation of the levers 52 to the links and T-shaped lever 49 being such that when either lever is depressed the long arm of the lever 49 will be swung from side to side and the radius bar and wheels correspondingly moved to guide the cultivator. The supporting bracket 46 extends

forwardly beneath the long arm of lever 49 and across its pivot with the radius bar and on the upper face of said portion of bracket 46 there is slidably mounted a latch member 54. This latch member is provided with depending front and rear lugs 54^a on each edge to retain it on bracket 46 and its forward end is provided with a thickened portion 54^b which has a forwardly extending lip 54^c corresponding in shape to the end of the body of the latch member and spaced therefrom to provide a horizontally extending notch or slot 54^d and the opposite end of the thickened portion is provided with a vertical slot or notch 54^e. The rear end of the body portion of latch 54 is formed with transverse notches or corrugations 54^f and with a laterally extending trigger 54^g. The latch 54 carries a complementary locking member 55, the under surface of which is formed with a tooth 55^a for engagement with the corrugations 54^f of latch member 54. Member 55 is also provided with a rounded ledge 55^b at its forward end and a backwardly extending trigger 55^c at its rear end. Member 55 is designed to be seated on latch member 54 in the manner illustrated in Figure 4 and the latch 54 is intended to be slidable back and forth on the bracket 46 and under member 55 which is held in fixed position with relation to bracket 46 by a locking device such as the hand wheel 56 which is threaded on a bolt 57 which extends through a longitudinal slot 54^h in member 54 and an aperture 55^a in member 55, the triggers 54^g and 55^c serving as holders while the adjustment of latch 54 is being made and the ledge 55^b serving to retain pin 50 in notch 54^d. The main frame of the cultivator has fixed thereto in any suitable manner a flat arcuate bar 58 which is concentric to the pivot 47 of bracket 46, which bar is positioned to be engaged in the slot or notch 54^d of latch member 54, as shown in Figure 4, thereby providing a support for the forward end of bracket 46 as the latch member 54 rides on this bar in all positions of adjustment. The arcuate bar 58 is provided at its center with a notch 58^a (Fig. 4) intended for interlocking engagement in one position of adjustment with a projection or tooth 54^b within the notch 54^d of the latch member 54. With the latch members 54 and 55 assembled on bracket 46, as above described, and the latch member 54 slidably engaged with bar 48, it will be seen that latch member 54 can be adjusted in a longitudinal direction on bracket 46 by releasing hand wheel 56 and sliding latch 54 backward or forward and because of its form and relation to notch 48^a and stud 50 depending from radius bar 24 it can be adjusted backwardly to a position where notch 54^d will engage stud 50, thereby locking bracket 46 and the beam shifting connections to the wheel steering means, or

by full forward adjustment the tooth 54¹ can be made to interlock with the notch 58^a, thus releasing the beam shifting connections from the wheel steering means and locking the beams against joint lateral movement. It will also be seen that when the latch is adjusted to a half way point, as in Figure 8, the beam shifting mechanism will neither be locked against movement nor locked to the steering means and the beams can be left to float freely by releasing lever 47^b.

The wheel steering means, above described, including the radius bar 24 and the beam shifting devices including the crossed arches 39, together with the means for effecting simultaneous or independent control of these devices, constitute a unitary organization which is the basis for a substantial part of applicant's present contribution to the cultivator art. These devices provide for the accomplishment of the spreading of the pairs of cultivator beams, holding the beams rigidly spaced during the operation of the cultivator and laterally shifting the beams by means of unitary connections between the upper front part of the cultivator frame and the forward ends of the beams. The crossed arched structures 39 form these unitary connections, combining in their functions a number of different improvements. By reason of the fact that the vertical supports 36 and 37 for the cultivator beams are, of themselves, free to swing laterally, the arches 39 constituting substantially the only means for properly controlling such swinging movement and holding the beams suitably rigidly spaced during operation of the cultivator. These arches also provide supports for the forward ends of the cultivator beams by reason of their horizontally extended ends. Furthermore, by reason of the fact that the arches are crossed, relative movements of the arches in opposite directions by the controlling mechanism above described give corresponding spreading movements of each pair of cultivator beams. Again, by reason of the fact that the controlling mechanism for the arches allows the latter to be moved in the same lateral direction in unison, all of the cultivator beams may be shifted in the same direction simultaneously. The controlling mechanism for the arches is operatively associated with the cultivator steering mechanism so that the beams may be shifted optionally, either simultaneously with the steering of the wheels, or independently thereof. Thus, the applicant has provided a two-row plural-beam pivot-axle cultivator having arched structures acting upon the forward ends of the beams to accomplish the various above described results in an improved and advantageous manner.

As means for effecting vertical adjustment 65 of each pair of beams and for applying re-

silient pressure to each pair of beams there is provided an adjusting lever 59 fixed to a stub shaft 60 journaled on the frame, which shaft has a forwardly extending crank arm 61 fixed thereto, the end of which is provided with laterally extending pins 61^a and an upright post 61^b. On this post there is slidably supported an equalizer bar 62 preferably of trussed form and provided with transverse struts or braces 62^a which are positioned to engage the laterally extending pins 61^a. The ends of the equalizer bar are connected to the beams of each pair by links 63 and on standard 61^b above the equalizer bar there is mounted a compression spring 64 which bears on a disk 65 resting on the equalizer bar. With this construction an equal pressure is imparted to each beam during normal operation as spring 64 is then compressed and the pins 61^a will be 85 out of contact with struts 62^a. When the beams are being raised the pins 61^a engage the struts 62^a and the equalizer bar and beams will be evenly raised.

With the construction and arrangement 90 of guiding and beam adjusting mechanism above described it will be evident that a cultivator has been provided in which the steering or guiding means may be used alone by moving latch 54 to a forward position 95 and if latch 54 is moved to its farthest extent, as in Fig. 9, that the beams will be held against lateral movement in unison and also that the guiding means and joint beam shifting means may be locked together by 100 moving latch 54 backwardly into engagement with stud 50, as in Fig. 7. It will also be evident that whatever the position of adjustment, the bell crank levers 44 will not be affected and that the adjustment of 105 the beams of each pair to and from each other can be made irrespective of whether the steering means is locked to the beam shifting means or not.

While a specific embodiment of my invention has been described by way of example, it is to be understood that variations in the construction are contemplated within the scope of the following claims.

I claim as my invention:

1. The combination with a cultivator having swiveled wheels provided with steering cranks and laterally shiftable beams, of operating mechanism for the wheels and beams comprising a radius bar connecting the 120 wheel cranks, a horizontally positioned lever with one end pivoted on the frame and the other pivoted to the radius bar and extending at right angles thereto, means for swinging said lever to steer the wheels, a laterally 125 swinging bracket pivoted on the frame in longitudinal alignment with said lever and extending across its point of connection to the radius bar, an arcuate bar fixed to the frame concentric with the pivot of said 130

bracket, a stud extending from the radius bar at its point of connection to said lever, and a sliding latch mounted on said bracket and having a portion resting on the arcuate bar, said latch being positioned between said bar and stud and provided with opposite engaging portions adapted to be interlocked with the stud or bar alternatively.

2. The combination with a cultivator having swiveled wheels, a radius bar connecting the wheels for joint steering movement, operating mechanism connected to the radius bar, and laterally shiftable cultivator beams; of connections between the beams for causing them to move laterally in unison, a laterally swinging bracket extending adjacent the radius bar and resting on a fixed frame member, said bracket being connected to said beam connections; and a latch shiftably mounted on said bracket and arranged to interlock with cooperating locking means on either said radius bar or said frame member.

3. The combination with a cultivator having two pairs of beams, swiveled wheels, a radius bar connecting the wheels for joint steering movement, operating mechanism connected to the radius bar, and laterally shiftable cultivator beams; of connections between the beams for causing both pairs to move in the same direction laterally in unison including means for simultaneously adjusting the beams in each pair to and from each other, a laterally swinging bracket supporting said beam connections and means carried by said bracket for connecting and disconnecting it from said radius bar.

4. The combination with a cultivator having swiveled wheels, a radius bar connecting the wheels for joint steering movement, operating mechanism connected to the radius bar, and laterally shiftable cultivator beams; of beam connections for simultaneously shifting the beams, and a slidable latch movable with said beam connections and adapted to be interlocked with the operating mechanism for the radius bar to connect the beam connections and radius bar for joint movement.

5. The combination with a cultivator having swiveled wheels, a radius bar connecting the wheels for joint steering movement, operating mechanism connected to the radius bar, and laterally shiftable cultivator beams; of beam connections for simultaneously shifting the beams, and a latch member movable with said beam connections and provided with means for interlocking with the radius bar in one position and for interlocking with a fixed part of the cultivator in another position.

6. A cultivator having a wheeled frame, two pairs of beams, a pair of arched members with their inner arms crossed and the ends of their arms extended horizontally and forming journals on which the forward

ends of the beams are mounted, each arch carrying one beam of each pair, and means for simultaneously shifting the arches laterally comprising a laterally movable support mounted on the frame, a pair of oppositely directed bell cranks pivoted on said support each with one arm linked to one of the arches, joint actuating means connected to the other arm whereby the arches may be oppositely shifted laterally, and means for moving said support from side to side whereby the arches may be simultaneously shifted laterally in the same direction.

7. A cultivator having a wheeled frame, two pairs of laterally shiftable beams, a pair of arched members with their inner arms crossed and the ends of their arms extended horizontally and forming journals on which the forward ends of the beams are mounted, each arch carrying one beam of each pair, and means for simultaneously shifting the arches laterally in opposite directions comprising a pair of oppositely directed bell cranks carried on the frame each with one arm linked to one of the arches, and joint actuating means connected to the other arms.

8. A cultivator having a frame, wheels supporting the frame, two pairs of beams, supports for the beams comprising a pair of arches with their inner arms crossed and the ends of their arms extended horizontally forming journals on which the forward ends of the beams are pivoted, supporting means between the frame and said arches, and beams, mechanism for shifting said arches to either side in unison, and means operable independently of said mechanism for shifting the arches towards and from each other, thereby correspondingly moving the beams of both pairs simultaneously.

9. A cultivator having a frame, wheels supporting the frame, two pairs of beams, a pair of arches pivotally supporting the forward ends of the beams, each arch supporting the outer beam of one pair and the inner beam of the other, supporting means between the frame and said arches and beams, mechanism for shifting said arches to either side in unison, and means carried by said mechanism for shifting the arches towards and from each other, thereby correspondingly moving the beams of both pairs simultaneously.

10. A cultivator comprising a frame, swiveled wheels supporting the frame, a pair of laterally shiftable arches suspended from the frame, the inner arms of said arches being extended and crossed, cultivator beams pivoted to the arms of said arches, guiding mechanism connected to said wheels and arches for shifting them towards either side in unison, and means for moving the arches towards and from each other, thereby correspondingly moving the beams of both pairs simultaneously.

11. A cultivator comprising a frame, swiveled wheels supporting the frame, two pairs of laterally shiftable cultivator beams suspended from said frame so as to be laterally swingable on longitudinal axes, guiding mechanism connected to said wheels and beams for shifting them towards either side in unison, and overlapped upright arch-shaped structures for simultaneously shifting the beams in each pair towards and from each other.
12. A multiple row pivot axle cultivator, comprising a frame, laterally shiftable cultivator beams pivotally associated with said frame, beam shifting mechanism for moving said beams with respect to rows of plants being cultivated, said mechanism including substantially bail-shaped structures, each of said structures having substantially vertical legs and a bight connecting said legs, each structure operatively overlapping the other and having its respective depending legs connected to corresponding alternate cultivator beams in such manner as to render the structures effective to laterally shift the cultivator beams, the shifting force of said branched structures being directly transmitted to the forward ends of the cultivator beams, thereby rendering said structures effective to exert their shifting effort directly upon the forward ends of the cultivator beams, laterally swinging supporting links laterally swingably supporting the bail-shaped structures from the frame, and control means operatively associated with said structures so as to move all of said cultivator beams simultaneously laterally, some of the beams in one direction, and the others in the opposite direction.
13. A pivot axle multiple row cultivator comprising a wheel supported cultivator frame, a plurality of laterally movable cultivator beams pivotally associated at their forward ends with said frame, substantially arch-shaped devices vertically arranged and operatively connected to the cultivator frame by pairs of pendulous links, each of said substantially arch-shaped devices having pivotal connections with the forward ends of alternate ones of said cultivator beams, said substantially arch-shaped devices overlapping each other and being operable in unison by unitary control means to laterally and simultaneously shift all of the cultivator beams by action which is directly transmitted to the forward ends of the cultivator beams.
14. A two-row plural-beam pivot-axe cultivator comprising, in combination, supporting wheels, a frame, pivot axles carried by the frame and rotatably receiving said wheels, a steering mechanism connecting the pivot axles for steering the cultivator, cultivator beams, substantially arch-shaped structures for associating the cultivator beams with the frame, said structures being arranged at the forward ends of the beams and having their entire weight borne by links depending from the frame, devices for moving said arch-shaped structures simultaneously in the same direction to laterally shift all of the cultivator beams in the same direction or in opposite directions to change the spacing of adjacent beams, and means for connecting the steering mechanism with said devices.
15. A multiple-row cultivator comprising a frame, supporting wheels, pivot axles associating the wheels with the frame, steering mechanism connecting the pivot axles for steering the cultivator, pairs of cultivator beams, overlapped substantially arch-shaped structures supported independently of the steering mechanism and movable in the same direction to shift all of the cultivator beams simultaneously in the same direction or in opposite directions to spread the beams at the will of the operator, and means for locking the steering mechanism to said structures at the will of the operator.
16. A multiple-row plural-beam pivot-axe cultivator having steering mechanism and a plurality of overlapped substantially arch-shaped structures relatively movable for spreading the cultivator beams, selectively operable means to lock the steering mechanism to said structures so that it will move transversely in unison therewith, and means for supporting said structures independently of the steering mechanism.
17. A multiple-row plural-beam cultivator having overlapped substantially arch-shaped vertical structures connected to the forward ends of the beams for spreading and laterally shifting the beams, the number of said substantially arch-shaped structures corresponding to the number of rows of plants operated upon by the cultivator, said substantially arch-shaped structures having independent pendulous supports allowing them to swing laterally as units.
18. A multiple-row plural-beam pivot-axe cultivator having a plurality of substantially arch-shaped structures overlapped in relation to each other and forming horizontal pivotal supports for the forward ends of the cultivator beams to form a single unitary organization combining the functions of spreading and laterally shifting the cultivator beams, said substantially arch-shaped structures having independent pendulous supports.
19. A multiple-row plural-beam pivot-axe cultivator comprising a frame, supporting wheels, pivot axles associating the frame with the wheels, pairs of cultivator beams, overlapped and substantially bail-shaped structures for spreading the pairs of the cultivator beams and for producing their plant.

- dodging movements, said structures having depending parts each of which is pivotally associated with a cultivator beam, and pairs of links depending from the frame and swingably supporting the depending parts of the bail-shaped structures and the beams so that the structures may swing laterally of the frame as units.
20. A multiple-row pivot-axle cultivator comprising pairs of beams, a pair of substantially arch-shaped beam shifting structures overlapping each other and having their ends extended horizontally to form journals on which the forward ends of the beams are mounted, each of said substantially arch-shaped structures carrying one beam of adjacent pairs of beams, and means for simultaneously shifting the substantially arch-shaped devices laterally comprising a laterally movable support mounted on the frame, oppositely movable parts mounted on the cultivator, each of said parts being linked to one of said substantially arch-shaped structures, operating means for said parts, and means for moving said support from side to side whereby the substantially arch-shaped devices may be simultaneously shifted laterally in the same direction. 75
21. A beam shifting mechanism for multiple-row cultivators, cultivator beams, said mechanism including overlapped substantially bail-shaped structures having substantially vertically depending legs, the lower ends of said legs forming pivotal front supports for the ends of the cultivator beams, means for increasing the amount of overlap of said bail-shaped structures to laterally shift the cultivator beams toward or from rows of plants and means for connecting the legs of one bail-shaped structure to the forward ends of alternate cultivator beams, said last named means holding the cultivator beams against lateral pivoting movement relative to the depending legs of the substantially bail-shaped structures. 80
22. A multiple-row cultivator having a wheeled frame, a plurality of pairs of laterally shiftable beams, a plurality of vertically arranged substantially arch-shaped structures having overlapped parts and other portions forming journals on which the forward ends of the beams are mounted, each substantially arch-shaped device connected to one beam of one pair of beams, and means for simultaneously shifting the substantially arch-shaped devices laterally in opposite directions to spread the beams of each pair, said shifting means comprising oppositely movable parts each being linked to one of the substantially arch-shaped devices, and actuating means for said shifting means. 85
23. A multiple-row cultivator comprising, a wheel supported frame, a plurality of cultivator beams, pendulous links arranged in pairs and connected to the frame and to the forward ends of the cultivator beams so as to permit the forward ends of the beams to swing freely laterally of the cultivator but preventing fore and aft movement of the beams, devices for connecting said pairs of pendulous links and for connecting the cultivator beams, said devices comprising operatively associated substantially arch-shaped structures acting upon the forward ends of alternate beams, these structures performing the functions of beam spreader arches, and holding the beams rigidly spaced and shifting the beams laterally to and from rows of plants as the cultivator is operated, the number of said substantially arch-shaped structures corresponding to the number of rows of plants operated upon by the cultivator. 90
24. A multiple-row plural-beam pivot-axle cultivator having overlapped substantially arch-shaped structures for transmitting plant dodging movements to the cultivator beams, said arch-shaped structures each having one leg integral with its mid-portion, a cultivator beam at each end of each of said structures, and connections between the forward ends of the beams and the ends of said structures allowing substantially free up and down swinging of the beams about the ends of the structures, but preventing relative lateral swinging movements of the beams connected to each structure. 95
25. In a two-row pivot-axle cultivator, a frame, supporting wheels connected to the frame by pivot-axes, four transversely aligned cultivator beams, beam supports whereby each beam is laterally swingably suspended from the frame at its forward end, an upwardly arched structure directly connecting the first and third cultivator beams at their forward ends, a similar upwardly arched structure directly connecting the second and fourth beams at their forward ends and intersecting the first arched structure, both of said arched structures being laterally swingably suspended from the frame by the same elements which so suspend the cultivator beams, a steering mechanism connecting said pivot-axes, and control devices connected to said steering mechanism and said arched structures for laterally moving the intersecting structures and the cultivator beams. 100
26. A cultivator comprising a frame, swiveled wheels supporting the frame, a pair of laterally shiftable upright overlapped arch-shaped structures suspended from the frame, duplicate pairs of cultivator beams pivotally mounted on the arch-shaped structures for independent movements as pairs, guiding mechanism connected to said wheels and overlapped arch-shaped structures for shifting them towards either side in unison, and means for moving the overlapped arch-shaped structures bodily. 105
27. A cultivator comprising a frame, swiveled wheels supporting the frame, a pair of laterally shiftable upright overlapped arch-shaped structures suspended from the frame, duplicate pairs of cultivator beams pivotally mounted on the arch-shaped structures for independent movements as pairs, guiding mechanism connected to said wheels and overlapped arch-shaped structures for shifting them towards either side in unison, and means for moving the overlapped arch-shaped structures bodily. 110
28. A cultivator comprising a frame, swiveled wheels supporting the frame, a pair of laterally shiftable upright overlapped arch-shaped structures suspended from the frame, duplicate pairs of cultivator beams pivotally mounted on the arch-shaped structures for independent movements as pairs, guiding mechanism connected to said wheels and overlapped arch-shaped structures for shifting them towards either side in unison, and means for moving the overlapped arch-shaped structures bodily. 115
29. A cultivator comprising a frame, swiveled wheels supporting the frame, a pair of laterally shiftable upright overlapped arch-shaped structures suspended from the frame, duplicate pairs of cultivator beams pivotally mounted on the arch-shaped structures for independent movements as pairs, guiding mechanism connected to said wheels and overlapped arch-shaped structures for shifting them towards either side in unison, and means for moving the overlapped arch-shaped structures bodily. 120
30. A cultivator comprising a frame, swiveled wheels supporting the frame, a pair of laterally shiftable upright overlapped arch-shaped structures suspended from the frame, duplicate pairs of cultivator beams pivotally mounted on the arch-shaped structures for independent movements as pairs, guiding mechanism connected to said wheels and overlapped arch-shaped structures for shifting them towards either side in unison, and means for moving the overlapped arch-shaped structures bodily. 125
31. A cultivator comprising a frame, swiveled wheels supporting the frame, a pair of laterally shiftable upright overlapped arch-shaped structures suspended from the frame, duplicate pairs of cultivator beams pivotally mounted on the arch-shaped structures for independent movements as pairs, guiding mechanism connected to said wheels and overlapped arch-shaped structures for shifting them towards either side in unison, and means for moving the overlapped arch-shaped structures bodily. 130

towards and from each other, thereby correspondingly moving the beams of both pairs simultaneously.

27. A two-row cultivator comprising, in combination, a frame, cultivator beams, swiveled wheels supporting the frame, a pair of laterally shiftable overlapped structures connected to the beams, means for connecting certain of the beams to each one of the overlapped structures on horizontal axes, supports pendently connected to the frame and pivotally supporting the overlapped structures, steering mechanism connected to said wheels and to said structures for producing plant dodging movements of the cultivator beams, and means for moving the overlapped structures simultaneously in opposite directions to vary the spacing of the beams.
28. A two-row cultivator comprising, in combination, a frame, wheels supporting the frame, two pairs of cultivator beams, a pair of overlapped structures respectively pivotally supporting the forward ends of separate pairs of the beams on horizontal axes, pendulous supports for carrying the entire weight of said structures, mechanism for shifting the overlapped structures to either side in unison, and means operable independently of said mechanism for shifting the overlapped structures towards and from each other, thereby moving the beams of both pairs simultaneously.

29. A cultivator having a frame, wheels supporting the frame, two pairs of cultivator beams, a pair of overlapped structures pivotally supporting the forward ends of the beams, each structure supporting the outer beam of one pair of beams and the inner beam of the other pair of beams, and independent supports connected to the frame and the ends of the overlapped structures and carrying the entire weight of the overlapped structures.
30. A two-row cultivator comprising, in combination, cultivator beams, duplicate interchangeable overlapped arch-shaped structures, and connections between the respective structures and beams including means holding the beams in fixed parallel relations.

31. A two-row cultivator comprising, in combination, a wheel supported frame, cultivator beams, duplicate interchangeable overlapped upright arch-shaped structures respectively connected to certain of the beams and swingably supported from the frame, and means for shifting the overlapped structures in unison to produce plant dodging movements of the beams by action upon the forward ends of the beams.

32. A multiple row cultivator comprising, in combination, cultivator beams, duplicate interchangeable, overlapped structures together forming means for transmitting plant dodging movements to the forward ends of

the beams, pendulous supports for said structures, and means acting upon the overlapped structures to shift them simultaneously in the same or in opposite directions.

33. A two-row cultivator comprising, in combination, a wheel supported frame, four cultivator beams carried by said frame, a single rigid member supporting the forward ends of the first and third cultivator beams, a second single rigid member supporting the forward ends of the second and fourth cultivator beams, and means connecting said rigid members for shifting them simultaneously in opposite directions.

34. A two-row cultivator comprising, in combination, supporting wheels, a frame carried by the supporting wheels, four cultivator beams carried by the frame, and means for supporting and shifting the cultivator beams laterally, said means comprising two rigid and oppositely movable members each of greater length than the distance between a pair of alternate beams and extending transversely of the frame near its forward end, and oppositely moving parts for shifting said members simultaneously, said rigid members being duplicates and acting as the direct pivotal supports for pairs of alternate beams.

35. A cultivator comprising a rigid frame, swiveled wheels supporting the frame, a pair of laterally shiftable interchangeable arch-shaped structures suspended from the frame in substantially upright positions, the inner parts of said arch-shaped structures being overlapped, cultivator beams having such connections to the arms of the arch-shaped structures that the beams are allowed free up and down movement but are prevented from having lateral movements relative to each other, guiding mechanism connected to said wheels and arch-shaped structures for shifting them towards either side in unison to produce plant dodging movements, and means for moving the arch-shaped structures towards and from each other, thereby correspondingly moving the beams of both pairs simultaneously to bring the beams into closer relation to plants.

36. A multiple row cultivator comprising, in combination, a frame, beams, pivot wheels supporting the frame, a pair of laterally shiftable upright overlapped structures connected to the beams and suspended from the frame in upright positions, bearings for connecting the beams to the overlapped structures on horizontal substantially co-axial axes, rigid connections between said bearings and the beams to prevent the beams from having lateral movement relative to each other, supports pendently connected to the frame and pivotally supporting the overlapped structures, steering mechanism connected to said wheels and to said structures for producing plant dodging movement of

the cultivator and the beams, and means carried by the steering mechanism for moving the overlapped structures simultaneously in opposite directions to vary the spacing of the beams.

37. A two-row cultivator comprising, in combination, cultivator beams, upright overlapped arch-shaped beam connecting structures movable in unison for producing plant dodging movements of the cultivator beams, and connections between said structures and the beams for preventing the beams from moving out of positions substantially perpendicular to the vertical planes of the structures.

38. A two-row cultivator comprising, in combination, pairs of cultivator beams, overlapped upright arch-shaped structures connected to the forward ends of the beams so as to normally prevent relative lateral movements of the beams, and means for shifting the overlapped structures in unison to produce plant dodging movements of the beams, said means including independently operable devices for shifting the arch-shaped structures simultaneously in opposite directions for spreading the pairs of beams.

39. A two-row pivot axle cultivator comprising, in combination, supporting wheels, a pivot axle for each wheel, an axle beam connecting the pivot axles, a front transverse support, means connecting the beam with the support so as to form a rigid frame therewith, cultivator beams free to have up and down pivotal movements, overlapped beam connecting structures suspended from the frame beneath the front support, a substantially upright pendulum rod for each cultivator beam pivotally connected at its upper end to the front support, a pivotal connection between the lower end of each pendulum rod and the forward end of the associated cultivator beam and one end of one of the overlapped beam connecting structures, a forwardly and downwardly inclined push bar pivotally connected at its upper end with the frame at a position near the axle beam and pivotally connected at its lower end with one end of a beam connecting structure, connections between each end of a beam connecting structure and a cultivator beam for normally preventing the beam from moving out of a position substantially at right angles to vertical planes passing through the ends of those structures, control means connected to the beam connecting structures for shifting the beams simultaneously, steering arms carried by the pivot axles, means connecting the steering arms for imparting simultaneous movement to the arms, and structure connecting the control means and the connecting means for imparting simultaneous lateral movement to the cultivator beams and the supporting wheels.

40. A two-row cultivator comprising, in

combination, supporting wheels, a frame carried by the supporting wheels, four cultivator beams, and means for laterally shifting the cultivator beams, said means comprising two rigid oppositely movable rods extending transversely of the frame near its forward end, each rod having a length greater than the distance between alternate beams, oppositely moving parts for shifting said rods simultaneously, and a direct pivotal connection between the forward end of each beam and a rod for preventing the beam from moving out of a position substantially perpendicular to the rod, said connection allowing up and down movements of the beam.

41. A cultivator comprising, in combination, a frame, ground wheels supporting the frame, four cultivator beams, oppositely movable supports movably mounted transversely of the frame at its forward end, the first support comprising a single rod extending through the forward ends of the first and third cultivator beams so as to hold them constantly in parallelism, the second of said supports comprising a single rod similarly extending through the ends of the second and fourth cultivator beams for maintaining them constantly perpendicular to the rod, and means for moving the supports simultaneously in opposite directions.

42. A two-row cultivator comprising, in combination, a frame, ground wheels for supporting the frame, four cultivator beams, interchangeable shifter rods of one-piece construction movably carried by the frame, direct pivotal connections between the first and third cultivator beams and one of said interchangeable shifter rods which extends from one of said beams to the other, direct pivotal connections between the second and fourth cultivator beams and the other of said shifter rods which extends from said second beam to said fourth beam, and means for shifting the interchangeable shifter rods in unison to produce plant dodging movements of the beams, said pivotal connections being rigid as related to lateral movements of the beams thereby preventing the beams from moving from positions perpendicular to the shifter rods.

43. A cultivator comprising, in combination, a frame, wheels supporting the frame, pivot axles for the wheels, a steering arm for turning each pivot axle, radius means tying the steering arms together for movement in unison, a lever construction for shifting the radius means transversely relative to the frame, cultivator beams beneath the frame, a beam connector structure transversely movable relative to the frame, and uniting means normally compelling the radius means and the beam connector structure to move in unison, said uniting means including a single element movable to three

positions of adjustment, the first adjustment locking the beam connector structure to the radius means, the second adjustment locking the beam connector structure to the frame, 5 and the third adjustment maintaining the beam connector structure in unlocked condition relative to the frame and relative to the radius means.

44. The combination with a cultivator 10 having swiveled wheels, radius means connecting the wheels for joint steering movement, operating mechanism connected to the radius means, and laterally shiftable cultivator beams; of beam connections for simultaneously shifting the beams and a latch member locking the radius means to the beam connections in one position of adjustment and having means for interlockingly engaging a fixed part of the cultivator in 15 another position of adjustment for maintaining the beam connections against movement relative to the frame.

45. As an article of manufacture, a cultivator arch constructed of a single rod and

comprising a beam supporting end, an integral upright part rising abruptly from said end at a small angle to the vertical, a top portion extending from the top of the upright part, and an inclined section of greater length than the upright part extending from the top portion to a position at a greater horizontal distance from the middle of the top portion than the position of the beam supporting end. 25

46. As an article of manufacture, a cultivator arch constructed of a single rod and comprising a beam supporting end, an integral upright part rising from said end, a top portion extending from the top of the upright part, and a bent section of greater 30 length than the upright part extending from the top portion to a position at a greater horizontal distance from the middle of the top portion than the position of the beam supporting end. 35

In testimony whereof I affix my signature.

SAMUEL K. DENNIS.
